UNITED STATES PATENT OFFICE

162,049

FENDER ORNAMENT FOR AUTOMOBILES

Handry J. Malachowski, Detroit, Mich.

Application July 2, 1949, Serial No. 3,667

Term of patent 7 years

(Cl. D14—6)

To all whom it may concern:

Be it known that I, Handry J. Malachowski, a citizen of the United States of America, residing at Detroit, in the county of Wayne and State of Michigan, have invented a new, original, and ornamental Design for a Fender Ornament for Automobiles, of which the following is a specification, reference being had to the accompanying drawing, forming part thereof.

Fig. 1 is a top plan view of the fender ornament for automobiles showing my new design,

Fig. 2 is a side elevation of the fender ornament for automobiles, and

Fig. 3 is a rear view of the fender ornament for automobiles.

I claim:

The ornamental design for a fender ornament for automobiles, as shown.

HANDRY J. MALACHOWSKI.
